United States Patent Office

Des. 203,261
Patented Dec. 21, 1965

203,261

CHAIR

Carl W. Sundberg and Montgomery Ferar, Southfield, Mich., assignors to American Seating Company, Grand Rapids, Mich., a corporation of New Jersey

Filed Nov. 17, 1964, Ser. No. 82,653

Term of patent 14 years

(Cl. D15—1)

The dominant features of our design reside in those portions shown in full lines on the drawing.

We claim:

The ornamental design for a chair, as shown and described.
